UNITED STATES PATENT OFFICE.

GEORGE M. COOPER, OF LITCHFIELD, MICHIGAN.

PRESS FOR PACKING WOOL.

Specification of Letters Patent No. 31,784, dated March 26, 1861.

To all whom it may concern:

Be it known that I, GEORGE M. COOPER, of Litchfield, Hillsdale county, Michigan, have invented a new and useful Machine 5 for Forming Wool, &c., into Bales; and I hereby declare the following to be a full, clear, and exact description thereof, reference being had to the annexed drawings, making part of this specification.

10 The object of this invention is a quickly operated device for pressing and binding wool into bales.

Figure 1 is a perspective view of a press embodying my invention. Fig. 2 is a vertical section of the same.

15 A is a rectangular box supported upon legs B and having two adjacent vertical fixed sides C, D. The remaining sides E and F are hinged by their lower edges to 20 the legs B.

H is an open barred rack hinged by one edge h to the stationary side C, and in its closed position its bars resting in notches c in the upper edges of the fixed side C and 25 the hinged side E.

I J is a hook and staple fastening for the top H in its closed position. Rods K hinged at top to the backs of the movable sides E and F and their lower ends passing through 30 staples K on the legs B serve to sustain the sides E and F at any open position that may be desired, and when the box is closed these rods also serve to guide the yoke L.

35 The yoke L consists of a rod bent into a rectangular form and having rollers M. The act of elevating this yoke acts to close the two open sides E and F. Said elevation is effected by means of a lever N whose cross head n is connected by rods O with the 40 yoke L.

P is a sliding floor or piston which, after the press has been filled and closed, is elevated by a rod p and lever Q.

R is a rack to enable the lever Q to be secured to any desired position.

45 S are grooves for the bands or cords by which the bale is tied.

The operation of pressing and tying the bale is very simple and rapid. The piston P being depressed and the two hinged sides E and F and the hinged top H thrown open—the cords or bands are laid in their grooves and the wool is inserted. The lever N is now depressed so as to elevate the yoke L and to close the sides E and F and thus 50 partly compress the wool. The top H is then brought down and hooked which acts to still further compress the wool. The box being now closed—the final and principal pressure is given—by the elevation of the 55 piston P. The lever Q being secured in the rack R the bale may be bound or tied in any approved way.

60 I claim herein as new and of my invention—

The arrangement of a box for pressing wool in bales; with the following elements to wit: two adjacent vertical fixed sides C and D, two adjacent hinged and movable sides E and F, supporting and guide rods 70 K—hinged top H, sliding yoke L and piston P; the whole being combined and operating together in the manner set forth.

In testimony of which invention, I hereunto set my hand.

GEORGE M. COOPER.
